UNITED STATES PATENT OFFICE.

JOHN H. GILES, OF AMSTERDAM, NEW YORK.

DESIGN FOR A KNIT SHIRT.

SPECIFICATION forming part of Design No. 23,187, dated April 10, 1894.

Application filed February 7, 1894. Serial No. 499,411. Term of patent 3½ years.

To all whom it may concern:

Be it known that I, JOHN H. GILES, of Amsterdam, in the county of Montgomery, in the State of New York, have invented and produced a new and original Design for Knit Shirts, of which the following, taken in connection with the accompanying drawing, is a full, clear, and exact description.

The annexed drawing represents a knit shirt folded in the usual manner to expose the front and collar thereof.

The salient feature of my design consists in alternate broad and narrow stripes A and B, running lengthwise of the body of the shirt, said stripes being separated by narrower stripes, C. Alternate wide and narrow stripes *a*, *b*, run around the body of the shirt at right angles to the stripes A and B. These stripes *a* and *b* are broken and do not cross the stripes C. All of the stripes, *a*, are of the

same width as are also the stripes *b*. The stripes *a* and *b* differ in color, but I do not wish to be limited to any particular shade or color of the yarns employed as they may be varied without limitation. The cross stripes 25 are narrower than the broad stripes, A, running lengthwise of the shirt.

The front of the shirt is provided with a central piece, or broad fly, and is ornamented by a lacing passing through the eyelets and 30 crossed, as shown.

What I claim is—

The design for a shirt substantially as herein shown and described.

In testimony whereof I have hereunto 35 signed my name.

JOHN H. GILES. [L. S.]
